UNITED STATES PATENT OFFICE.

JEROME C. JOSLIN, OF KEENE, NEW HAMPSHIRE.

FLASK FOR BUILDING CEMENT WALLS.

974,673.

Specification of Letters Patent.

Patented Nov. 1, 1910.

Application filed November 27, 1907. Serial No. 404,170.

To all whom it may concern:

Be it known that I, JEROME C. JOSLIN, a citizen of the United States, residing at Keene, in the county of Cheshire and State of New Hampshire, have invented a new and useful Improvement in Flasks for Building Cement Walls, of which the following is a specification.

My invention relates to flasks for building cement walls and more particularly to flasks for building foundations, piers and abutments, the object being to provide a flask which can be raised after it has been filled with cement so as to form a continuous wall without removing the mold.

Another object of my invention is to provide a flask with very novel means for raising it after the concrete has congealed, so that it can be readily filled again.

Another object of my invention is to provide a flask with pivoted sides so that they can be swung outwardly when forming a battered or ornamental wall so as to clear the figure work before the flask is raised.

Another object of my invention is to provide a flask which can be easily and quickly adjusted so as to mold any width wall.

A further object is to provide very novel means for supporting and guiding the flask when being raised.

A still further object of my invention is to provide a central core in connection with the flask so that hollow walls can be molded.

With these objects in view, the invention consists in the novel features of construction, combination and arrangement of parts, hereinafter fully described and pointed out in the claims.

In the drawings forming a part of this specification:—Figure 1 is a side view of my improved flask showing it arranged on the walls in position to be filled. Fig. 2 is an end view of the flask, the end being partly broken away. Fig. 3 is an end view of a guide-member adapted to be secured to the side of the mold for holding it in a vertical position on the wall. Fig. 4 is a section taken on the line 4—4 of Fig. 2 showing a portion of the core. Fig. 5 is a perspective view of my improved flask one side and end being removed, and Fig. 6 is a top plan view of a flask to be used around angles in walls.

In the drawings A and B indicate the sides which are provided with strap-brackets A' B' at their ends, in which the ends C are adapted to be secured, the sides being of

any desirable length, and having spaced jaws D and E secured on their outer faces which are provided with slotted upper ends which are pivotally and adjustably mounted on cross-bars F by bolts D', E', one end of the cross-bars being provided with spaced openings F', in which the bolts D' are adapted to fit, so that the sides can be adjusted to mold any width wall desired. The jaws being held in a vertical position by set-screws D'', E'', which engage the upper edges of the cross-bars, and hold the same in a rigid position, so as to prevent the same from turning on the bolts D', E', and it will be seen that by loosening these bolts, the slides can be swung outwardly a slight distance so that when molding an ornamental wall the sides will clear the figure work before the flask is raised, as it is only necessary to have the slides swung a slight distance to enable the slides to be drawn upwardly without any danger of injuring the face of the wall, as will be hereinafter fully described.

Mounted on each of the cross-bars F are slotted blocks G and H, which are provided with vertical threaded bores, in which are mounted turn-screws I and J provided with disks I' J' at their lower ends loosely mounted thereon and square upper ends forming wrench-receiving heads so that they can be readily turned. Vertical square bores are formed in the blocks to the other side of the cross-bars, in which are slidably mounted pins K, L having angled ends which are secured in the blocks by set-screws, which engage the pins and hold them in an adjusted position, as will be hereinafter described. Notched guide-members M are secured to the sides of the flask after it has reached a height above the ground, which are adapted to engage the sides of the molded wall and hold the flask securely thereon.

When it is desired to form a hollow wall yokes N are secured on the bars between the blocks, by set-screws N' the lower ends of the yokes having the upper ends of screws O, pivotally mounted between the same which carry the core P which is normally held midway between the walls of the flask and is provided with notches in its lower edge, in which the anchor-irons Q fit, for securing the two walls together.

In Fig. 6 I have shown a flask especially constructed for molding angles in walls, the sides S being connected to short pieces T by

angled irons U, which are provided with slots which fit over staples secured in the sides, and are secured in place by pins. It of course being understood that this only 5 applies to the outside wall of the flask, the inside walls being secured to a piece V, by angled irons W.

The operation is as follows:—The sides and ends are placed in position, so as to mold 10 any width wall desired, the pins are then shoved downwardly to hold the same in position and the flask is filled with cement and allowed to harden. The screws are then operated the pins being first hit with a hammer 15 once or twice so as to loosen the same as the screws are turned, the sides and ends will be raised until they reach the top of the walls. The guide-members are then placed 20 on the sides so as to hold the mold in position, and the pins are forced downwardly until they engage the top of the wall which supports the mold. The screws are then turned so as to bring them up above the plane of the top of the sides and the mold 25 is then filled with cement, this being repeated

until the desired height of the wall is obtained. The operation for molding a hollow wall being the same, except that the core is placed between the walls. It will be seen that when it is desired to mold a wall with 30 an ornamental face, the sides of the flask can be swung outwardly sufficiently by loosening the set-screw, so as to clear the figure work before the mold is raised.

Having thus fully described my invention, 35 what I claim as new and desire to secure by Letters Patent is:—

In a flask of the kind described, the combination with cross-bars, of jaws adjustably mounted on said cross-bars carrying 40 sides, ends carried by said sides, depending guide-members carried by the sides, and means slidably mounted on the cross-bars for raising and supporting said mold, for the purpose described.

JEROME C. JOSLIN.
